CLAIM

(21) Appl. No.: **29/576,968**

The ornamental design for an electronic pillar candle with matrix flame, as shown and described.

(22) Filed: **Sep. 8, 2016**

DESCRIPTION

Related U.S. Application Data

(62) Division of application No. 29/512,312, filed on Dec. 18, 2014, now Pat. No. Des. 767,799.

FIG. 1 is a front view of the electronic pillar candle with matrix flame of the present disclosure;

(51) **LOC (10) Cl.** **26-04**

FIG. 2 is a rear view of the electronic pillar candle with matrix flame of FIG. 1;

(52) **U.S. Cl.**

FIG. 3 is a side view of the electronic pillar candle with matrix flame of FIG. 1;

USPC **D26/4**

FIG. 4 is a top view of the electronic pillar candle with matrix flame of FIG. 1;

(58) **Field of Classification Search**

FIG. 5 is a bottom view of the electronic pillar candle with matrix flame of FIG. 1;

USPC D26/1-4; 313/313, 315, 316, 317, 318, 313/493; 315/52, 53, 56, 57, 58

FIG. 6 is a top, front, right perspective view of the electronic pillar candle with matrix flame of FIG. 1; and,

CPC H01J 5/00; H01J 15/00; H01J 5/48; H01J 5/50; H01J 19/54; F21V 5/00

FIG. 7 is a bottom, rear, left perspective view of the electronic pillar candle with matrix flame of FIG. 1.

See application file for complete search history.

The broken lines in the above figures are provided for purposes of illustration and form no part of the claimed design of the present application.
